UNITED STATES PATENT OFFICE.

EDWARD NOVOTNY, OF STRUTHERS, OHIO.

CAR-DERAILED.

1,188,554.

Specification of Letters Patent. Patented June 27, 1916.

Application filed February 29, 1916. Serial No. 81,218.

To all whom it may concern:

Be it known that I, EDWARD NOVOTNY, a citizen of the United States, residing at Struthers, in the county of Mahoning and 5 State of Ohio, have invented certain new and useful Improvements in Car-Derailers, of which the following is a specification.

This invention relates to certain new and useful improvements in car derailers.

10 The primary object of the invention is the provision of a derailing truck device especially adapted for quick positioning upon a railway track for overturning a run-away car such as a mine car which has become 15 detached from the train or locomotive.

A further object of the invention is to provide a derailing device adapted to be readily positioned for movement upon a railway track and being so constructed that 20 an oncoming run-away car will partially mount upon the same and be overturned at the side of the track thereby.

The construction of the device herein set forth contemplates a car member that may 25 be positioned against movement upon a track, the same being provided with a track section, one rail of which is elevated and adapted for sliding upon the track rails while a pivoted elevating member for the 30 wheels of the car to be derailed is carried by the said car member of the device.

With these general objects in view and others that will appear as the nature of the invention is better understood, the same 35 consists in the novel construction, combination and arrangement of parts hereinafter more fully described, illustrated in the accompanying drawings, and then claimed.

In the accompanying drawings forming 40 a part of this application and in which like designating characters refer to corresponding parts throughout the several views:— Figure 1 is a central longitudinal vertical sectional view taken through a portion of a 45 railway track provided with the present device, a portion of the latter being shown in side elevation. Fig. 2 is a top plan view thereof. Fig. 3 is a side elevation of a portion of the device mounted upon a track, 50 parts being illustrated in their inoperative positions. Fig. 4 is a vertical transverse sectional view through a track and a portion of the device. Fig. 5 is a perspective view of one of the sliding rail members broken 55 away. Fig. 6 is a perspective view of one of the connecting pull bars. Fig. 7 is a

sectional view through the connection between a pull bar and rail section, and, Fig. 8 is a perspective view of one of the connecting bolts employed with the device. 60

It will first be understood that the present invention is designed for the purpose of derailing an oncoming car or other piece of railway rolling stock and is herein illustrated in connection with a usual form of 65 railway track 10 having oppositely-arranged rails 11.

A slideable track section 12 is provided which is pivotally attached to a small car 13 such as a hand car and by which means 70 the track section 12 may be slidably moved along the rails 11 by pushing or otherwise impelling the car 13. The aforementioned track section 12 comprises one rail 14 herein termed the lower rail which is of inverted channel-shaped formation for readily mounting slidably upon one of the rails 11 as best illustrated in Fig. 4 of the drawings. Another or elevated rail 15 of the track section 12 is positioned opposite the 75 lower rail 14 being connected in parallelism by means of suitable braces 16. This elevated rail 15 is of tapered formation having a bottom channel 17 for slidably mounting the same upon the rail 11 which lies opposite the track section lower rail 14 while a double flanged wheel 18 is journaled beneath one end of the elevated rail 15 for running upon the adjacent track rail 11 and whereby the forward end of the rail 90 15 is elevated above the track. The aforementioned hand car 13 is provided with oppositely-arranged pull bars 19 which have their forward ends 20 pivotally mounted upon the forward axle 21 of the hand car 95 while the rear ends of the pull bars 19 are provided with transverse perforations 22 adapted for the reception of bolts 23, which latter also pass through perforations 24 in the adjacent ends of the rails 14 and 15 100 while cotter pins 25 are employed for retaining the bolts in position and whereby, as will be evident, the track section 12 is attached to the car 13 so that a movement of the said car upon the railway track slidably moves the track section 12 therealong. 105

Derailing blocks or arms 26 are oppositely positioned journaled to the rear axle 27 of the car 13 and are each provided with arcuate base ends 28 which are formed laterally slanting outwardly and forwardly in the direction of the lower rail 14, it being 110

noted that said blocks 26 are of substantially triangular contour.

A windlass 29 is arranged upon the hand car 13 providing a drum 30 readily turned 5 by means of a crank 31 and having a rope 32 wound thereon and provided with a terminal ring 33. An elevating cord 34 is threaded through the ring 33 and has its opposite ends secured to the upper adjacent 10 sides of the blocks 26 and whereby as will be evident, a reeling up of the rope 32 will elevate the blocks 26 to the position shown in Fig. 3 of the drawings.

An arrangement of chock block 35 is provided for the rear wheels 37 of the car 13 15 and similar means may be also provided for the forward wheels thereof if desired, the said chock block 35 being operatively moved by means of any desirable form of adjusting lever 36 and whereby the block may be positioned beneath the wheels 36 for preventing any forward movement of the said car.

It will be seen that when the car 13 and 25 track section 12 are mounted upon the railway track rails 11 and the chock block 35 placed in its operative position for maintaining the car 13 stationary, the block 26 may be lowered by means of the crank 31 so 30 as to rest upon the connecting bars 19 at points directly in advance of the rails 14 and 15. An oncoming run-away car upon the track 10 will pass upon the rails 14 and 15 and by reason of the elevated position of 35 the forward end of the rail 15, the car will be tilted toward the lower rail 14. When the forward wheels of the run-away car engage the curved slanting faces 28 of the elevating blocks 26, the said blocks will tilt 40 upwardly which will increase the tipping of the run-away car and will effect a dumping of the same laterally off of the track section 12 and clear of the railway track 10, thus completely derailing such car without 45 any injury to the present device and preventing the run-away car from doing any further damage by its continued uncontrolled travel upon the track 10.

While the form of the invention herein 50 shown and described is what is believed to be the preferred embodiment thereof, it is nevertheless to be understood that various forms, modifications and arrangements of the parts may be made without departing 55 from the spirit and scope of the invention as claimed.

What I claim as new is:—

1. A derailing device comprising a car,

Copies of this patent may be obtained for five cents each, by addressing the "Commissioner of Patents, Washington, D. C."

a slideable track section having a portion of one rail thereof inclined, pivotal connection 60 means between the said track section and the forward axle of the said car, and adjustable elevating means pivotally carried by the rear axle of the car and normally positioned adjacent the forward end of the 65 said track section.

2. A device of the class described, comprising a car, a brake for the said car, a traction section having rail-receiving longitudinal grooves within the side rails 70 thereof, an elevating wheel journaled beneath the forward end of one of the rails of said section, and connecting bars attached to the forward ends of the rails of said section and pivotally attached to the forward 75 axle of the said car.

3. A device of the class described, comprising a car, a brake for the said car, a traction section having rail-receiving longitudinal grooves within the side rails 80 thereof, an elevating wheel journaled beneath the forward end of one of the rails of said section, connecting bars attached to the forward ends of the rails of said section and pivotally attached to the forward axle of 85 the said car, substantially triangular-shaped elevating blocks oppositely pivoted to the rear axle of the said car and having arcuate rearwardly-extending base edges inclined in the same direction and normally positioned forwardly of the forward end of the 90 said track section, and adjusting means for the said blocks carried by the said car.

4. A derailer for run-away rolling stock comprising in combination with a railroad 95 track, a hand car positioned thereon, a lower rail slidably mounted upon the said track, an upper rail in parallelism with the said lower rail and being tapered with its rear end slidably mounted upon the said track, an elevating wheel journaled in the forward end of the said upper rail, connecting bars attached to the forward ends of the said rails and pivotally attached to the forward axle of the said car, triangular-shaped elevating blocks oppositely pivoted to the rear axle of the said car and having concaved base edges inclined toward the said lower rail and normally positioned upon the said connecting bars adjacent the forward 105 ends of the said rails, and adjusting means carried by the said car and shiftably attached to the upper sides of the said blocks.

In testimony whereof I affix my signature.

EDWARD NOVOTNY.
